UNITED STATES PATENT OFFICE.

GEORGE N. TAYLOR, OF EAST PROVIDENCE, RHODE ISLAND, ASSIGNEE TO UNIVERSAL WINDING COMPANY, OF BOSTON, MASSACHUSETTS, A CORPORATION OF MASSACHUSETTS.

TRAVERSE MOTION FOR WINDING MACHINES.

1,427,035.

Specification of Letters Patent. Patented Aug. 22, 1922.

Application filed October 13, 1921. Serial No. 507,496.

To all whom it may concern:

Be it known that I, GEORGE N. TAYLOR, of East Providence, in the county of Providence, State of Rhode Island, a citizen of the 5 United States, have invented certain new and useful Improvements in Traverse Motions for Winding Machines, of which the following is a specification.

My invention relates to winding machines 10 and consists of improvements in the traverse-mechanism for operating the thread-guide which deposits the windings in place to build up a cop or package of the desired form.

My invention relates more particularly to 15 cone-winders for winding conical cops or packages and one object of the improvement is to so regulate the laying of the yarn on the cone as to cause the latter to be built up with a gradually increasing pitch or taper on 20 its surface.

Another object of the invention is to provide means for controlling the reciprocation of the thread-guide to effect a quick reversal of motion at the end of its traverse, whereby 25 the thread or yarn coils will be disposed with abrupt bends at the extreme of traverse to prevent overruns or "cobwebs" on the end of the package.

Further objects of the improvement are 30 set forth in the following specification which describes a preferred embodiment of the invention as illustrated by the accompanying drawings. In the drawings:

Fig. 1 is a front elevation of a portion of 35 a winding machine showing my improved traverse-motion as applied to use thereon; and

Fig. 2, an end elevation of the same, taken 40 in part section on the line 2—2 of Fig. 1.

As herein shown my invention is applied 45 to a winding machine of the friction- or drum-driven type comprising, essentially: a rotating drive-roll or friction-drum D; a winding-mandrel C, on which the cop or package is wound through frictional contact 50 with the roll; and a reciprocating thread-guide G which traverses the yarn or thread back and forth to deposit it in helical coils on the mandrel.

The structure and arrangement of these 55 essential elements of the winding mechanism are well known to those versed in the art, and in other types of machines, to which my present invention is also adapted, the wind-

ing-mandrel is driven positively instead of 55 by contact of the cop with a drive-roll.

In the present drawings I have shown only a small section of a multiple machine which, as usually arranged, comprises a series of winding units each complete in itself. As here illustrated the drive-roll D is mounted on, and driven from, a continuous shaft 2 which carries a series of similar rolls for the other winding units. Arranged above each drive-roll D is a winding-mandrel C 60 which receives the paper or fiber cop-tube X on which the package is wound. The winding-mandrel C is usually supported from a swinging arm or arms which allows it to recede from the axis of the drive-roll 65 with the growth of the winding, a preferred construction for this part of the mechanism being shown and described in my copending application Serial No. 485,278, filed July 16, 1921, but not herein illustrated. Suffice it 70 for the present to state that as the yarn is built up on the mandrel C the latter rises away from the drive-roll D to accommodate the growth of the package, and the mandrel also receives a tilting motion in relation to 75 the axis of the roll to compensate for the variation in the taper on the surface of the cone or package being wound. In this manner the surface of the winding is maintained 80 constantly in contact with the periphery 85 of the drive-roll whereby the latter imparts rotation to the cop or package.

Each drive-roll D is provided with a thread-guide G arranged in close association therewith and adapted for reciprocation in 90 a path parallel with the axis of the roll. As herein shown the thread-guide G consists of a blade-like member formed with a thickened head at the top which is provided with a slot or groove 3 through which the 95 thread or yarn y feeds to the package. The thread-guide G is mounted on a crosshead 4 attached to a horizontal sliding rod or traverse-bar 5. Usually the traverse-bar 5 extends the length of the whole machine and 100 carries a series of guides for the several winding units. As herein illustrated the traverse-bar 5 is mounted to reciprocate in bearings 6 supported from standards or brackets 7 fastened to the main frame F of 105 the machine. Also fixedly supported from the brackets 7 is a rod 8 arranged below the traverse-bar 5 in parallel relation thereto.

The crosshead 4 is constructed with loop-shaped ears 9 clamped around the traverse-bar by means of screws 10, and is provided with a depending plate-portion 11 formed 5 with a loop 12 at the bottom which straddles the lower rod 8 to serve as a guide or runner as it slides thereon. Projecting forwardly from the front of the plate-portion 11 of the crosshead 4 are two ears 13 bent outwardly 10 from the sides of a central opening 14 in the plate. The ears 13 are adapted to abut the sides of a roller 15 pivoted on a stud 16 carried at the upper end of an oscillating traverse-arm or lever 20 and projecting 15 through the opening 14 in the crosshead.

The traverse-arm or lever 20 is pivoted to a slide or cross-head 21 so that the lever may be given a reciprocating motion in addition to its oscillating movement about the axis 20 of its pivot. As shown in the drawings, the slide 21 is formed with two lower bearings 22 which encircle a horizontal rod 23 held at its ends in fixed bearings 24 on the machine frame F. Arranged above and parallel with 25 the rod 23 is a second rod or bar 25, preferably of rectangular cross-section, which is held at its ends in the bearings 24. The slide 21 is provided with an upper forked extension 26 which straddles the bar 25 so 30 that the latter with its companion rod 23 form a track or guideway for the slide.

As shown more particularly in Fig. 1, the traverse-arm or lever 20 is substantially L-shaped or of bell-crank type and is pivoted 35 to the slide 21 at the junction of its two right-angled arms 27 and 28. The pivot for the lever 20 may conveniently consist of a pin or stud 29 projecting forwardly from a hub 30 on the slide 21 and carrying a nut 40 31 at its end for holding the lever in place thereon. The stud 29 also projects rearwardly through the hub 30 and is provided with a flange or collar 32 abutting the end of the hub, see Fig. 2. Outwardly beyond 45 the flange 32 the stud 29 is extended to form a bearing 33 for a roller or bowl 34 which engages with the helical groove 35 of a traverse-cam 36 of usual construction. As shown in Fig. 2, the cam 36 has a circular 50 rim 37 supported from spokes 38 radiating from a hub 39 which is secured to a shaft 40. The shaft 40 is driven through suitable gearing or other transmission-means, not herein shown, connected with the source of 55 power which drives the machine. In the type of machine herein shown a single traverse-mechanism, comprising the cam 36 and its cooperating elements, serves to transmit motion to all of the several thread-guides G 60 mounted on the sliding traverse-bar 5. If desired, however, a separate traverse-motion may be employed for each winding unit and it is to be understood that the present improvement is applicable to either type of 65 machine.

It will be seen that the traverse-slide 21 slides on its track 23, 25 under the reciprocating motion imparted thereto from the cam 36. It will likewise be obvious that the traverse-lever 20, being carried on the slide 70 21, will be reciprocated therewith and in addition to this reciprocation an oscillating motion is also imparted to the lever. This latter motion of the lever 20 is effected by means of a fixed cam or guiding-track 41 75 acting on the horizontal arm 28 of the lever 20. As shown more particularly in Fig. 1, the cam or track 41 consists of an arcuate plate which is fastened to the machine frame F by means of bolts 42 passing through 80 bosses 43 at its ends. The plate 41 is formed with a curved guiding-slot or cam-groove 44 terminating at its upper left-hand end in a sharp reverse curve or bend 45. The cam-slot 44 engages with a roller or bowl 46 85 pivoted on a stud or pin 47 at the outer end of the arm 28 of the lever 20, see Fig. 2. It will be obvious that if the traverse-arm or lever 20 were held fixed on the slide 21 it would receive a uniform reciprocating motion from the main cam 36, but, being pivotally mounted on the slide with its arm 28 90 acted upon by the curved cam-groove 44, the lever will be rocked back and forth during its reciprocation with the slide. This rocking or oscillating movement of the lever 20 acts to impart an increment of motion to the upper end of the arm 27 of the lever as the latter moves to the right, as viewed in Fig. 1, and a corresponding decrement of movement as it moves in the opposite direction. This variable motion of the lever 20 is communicated to the traverse-bar 5 and the thread-guide G mounted thereon in the manner and for the purpose as later explained. 95

Having now described the structure and arrangement of my improved mechanism in detail its method of operation will next be explained: The winding machine is prepared for operation by placing a paper cop-tube X, or other package support, on the cone-holder or winding-mandrel C with the thread or yarn y leading thereto through the eye 3 in the thread-guide G. In most machines of the present type the driving- 100 roll or drum D is driven continuously and when the cop-tube X is placed in contact therewith, as shown in Fig. 1, the winding-mandrel C will be rotated from the frictional contact of the tube with the peripheral 105 surface of the roll. As the winding-mandrel C is thus driven from the drive-roll D the yarn y will be wound onto the tube or support X, and meanwhile the thread-guide G is reciprocated back and forth longitudinally of the mandrel in the manner as next 110 explained.

The cam 36 is driven from its shaft 40 through the medium of suitable gearing or other transmission mechanism as above ex- 115 120 125 130

plained. As the cam 36 is rotated its helical groove 35 acts on the roller 34 to slide the traverse-slide 21 back and forth on its horizontal track 23, 25 and the traverse-arm 20 being mounted on the slide is reciprocated therewith. It will be noted from Fig. 1 of the drawings that the throw of the cam 36 is somewhat less in extent than the length of the cap-tube X, but that the coils of yarn y 10 are laid with a traverse substantially equal to the length of the tube. That is to say, the cam 36 imparts to the slide 21 only a portion of the full length of traverse of the thread-guide G and the added motion is 15 communicated to the guide to complete its full traverse by causing an increment of movement at the upper end of the traverse-lever 20. This increment of movement is effected by rocking the lever 20 about its 20 pivot 29 through the action of the cam or track 41 on its horizontal arm 28. It will be noted that the cam-slot 44 of the track 41 curves downwardly to the right, as viewed in Fig. 1, and hence the arm 28 of the lever 25 20 will be depressed as its roll 46 travels outwardly toward the right-hand end of the slot. This action results in causing the upper end of the arm 27 of the lever 20 to be rocked to the right whereby the thread-guide G connected thereto is advanced beyond the limit of throw of the traverse-slide 21. It has before been explained that the arm 27 of the lever 20 is connected to the 30 crosshead 4 by means of the roller 15 which 35 engages the two opposite ears 13, and through this arrangement the arcuate movement of the roller under the rocking action of the lever 20 is compensated for by its sliding action between the two ears.

40 The cam 36 is driven at a constant speed and the traverse-slide 21 is therefore reciprocated with a uniform motion, but it will be obvious that as the lever 20 is oscillated while moving with the slide the crosshead 4 will not only be given an increment of movement over that of the slide 21, but it will also be operated at an accelerated speed as it moves to the right, and with a corresponding retardation as it moves to the left. 45 This change of speed in the movement of the crosshead 21 is communicated to the thread-guide G whereby the latter is reciprocated with a differential motion as follows: Starting at the base of the cone-holder C the speed of the guide is accelerated as it moves toward the tip or apex end thereof, and at the reversal of its movement the speed of the guide is gradually retarded as it traverses back toward the base end of 50 the holder. The purpose of this acceleration in the speed of the guide as it moves toward the tip of the cone, and retardation as it moves back toward the base, is to cause the yarn to be laid in helices which have an 55 increasing pitch or lead toward the small

end of the cone. Stated briefly, the coils or turns of the yarn are laid closer together at the base of the cone than at its apex end and therefore the yarn builds up faster at the larger end of the package than at the 70 smaller end. The result of this method of laying the yarn on the cone-holder is to cause the cone or package to build up with a gradually increasing mass at its base so that the taper on the surface of the cone is 75 constantly increased. This method of building the cone with a gradually increasing pitch or taper on its surface is of advantage as making for a freer delivery of the yarn in unwinding it for delivery to other processes. It is well known in the art that in winding on the first layers of yarn in the cone the coils have a greater tendency to slip or slide out of place than when the 80 package has assumed a substantial diameter. That is to say, the coils will not hold in place as well on a surface of relatively small diameter and consequently the taper of the cone-holder must be restricted within certain prescribed limits. On the other 85 hand, after a certain amount of yarn has been built up on the cone-holder the coils of winding will hold in place better and therefore the taper of the surface may be increased. It is of advantage to wind the cone 90 with as great a pitch or taper on its surface as is practicable in order to insure a free delivery of the yarn in unwinding it, and hence it has become the preferred practice to start the winding with a minimum taper or 95 pitch to the layers and to gradually increase the taper as the cone grows in diameter. The object of my improved traverse-motion is therefore to effect a system of laying the 100 coils of yarn in place on the cone-holder 105 whereby a greater mass is built up toward the base end of the cone so that the taper or pitch on its surface increases from the prescribed minimum to the desired maximum. In this way my invention provides for 110 winding a cone of the preferred type in which the layers of winding gradually assume a greater inclination to the axis of the package so that as the latter attains its full diameter the yarn will deliver more 115 freely from its outer surface in unwinding it for delivery to other processes.

120 As an added feature of improvement my invention also provides for a quick reversal of the traverse of the yarn at the base end of the cone for the purpose of preventing overruns or cobwebs. It has before been explained that the cam-groove 44 in the track 41 which acts on the transverse-lever 20 has an abrupt bend 45 at its upper end, see Fig. 125 1. The purpose of this reverse bend 45 in the cam-groove 44 and the manner in which it controls the movement of the lever 20 is as follows: As the lever 20 moves to the left, as viewed in Fig. 1, the roller 46 on its arm 130

28 travels up the curved incline of the track 44 and just as the traverse-slide 21 reaches the end of its throw in this direction the roller enters the sharp bend 45 of the groove 44. The bend 45 of the groove will therefore act on the lever to give a quick rocking action thereto whereby its upper end is moved to the left with a quick, sharp throw and immediately the traverse-slide 21 10 starts to the right again the action of the bend 45 in the cam-groove will cause a sharp reversal of the movement of the lever. Stated briefly, the sharp bend 45 in the cam-groove 44 acts on the roller 46 to rock the 15 lever 20 to whip its upper end to the left and then to the right again with an accelerated rate of movement, and this motion is communicated through the cross-head 4 to the thread-guide G to prevent the latter 20 from making a dwell or pause at the end of its stroke. Through this action on the thread-guide G the latter is caused to lay the 25 yarn in place on the surface of the winding with the coils terminating in sharp bends or "knuckles" at the base end of the cone so that there is less tendency for the yarn to fall over the edge of the cone to form loose loops or "cobwebs", as they are termed.

It will be observed from the foregoing description that my invention provides an improved traverse-mechanism for controlling the "lay" of the yarn in building up the package whereby a cone of the required shape may be produced; and that the invention 30 operates further to provide a quick reversal in the traverse of the yarn to prevent overruns or cobwebs at the end of the package where they are most liable to occur. If desired, the quick-reversing means may be 35 arranged to operate on the thread-guide at both ends of its stroke but usually there is less tendency of the yarn to overrun the nose 40 end of the cone because the guide is moving faster at this point and its reversal of motion 45 is therefore naturally quicker.

While I have herein shown and described a preferred embodiment of my improved device it is obvious that various modifications may be made in the structure and arrangement of its mechanism without departing 50 from the spirit or scope of the invention; therefore, without limiting myself in this respect, I claim:

1. In a winding machine, the combination 55 with a rotatable cop-holder, of means for traversing the yarn on the holder, a cam for reciprocating the traverse-means, and means intermediate the cam and the traverse-means to effect a differential movement of 60 the latter whereby the yarn is traversed with increasing speed toward one end of the holder and decreasing speed toward the opposite end thereof.

2. In a winding machine, the combination 65 with a rotatable cop-holder, of means for

traversing the yarn on the holder, a cam for reciprocating the traverse-means, and a second cam acting on the traverse-means to effect a differential rate of movement thereof whereby to cause the yarn to be traversed 70 with accelerated speed toward one end of the holder and correspondingly retarded speed toward the opposite end thereof.

3. In a winding machine, the combination with a rotatable cop-holder, of a reciprocable 75 thread-guide for traversing the yarn on the holder, a cam for reciprocating the thread-guide with a constant extent of traverse, and a second cam acting on the thread-guide to impart an accelerated speed of traverse 80 to the latter as it moves in one direction and a diminishing speed as it moves in the opposite direction.

4. In a winding machine, the combination with a rotatable cop-holder, of a reciprocable 85 thread-guide for traversing the yarn on the holder, means for reciprocating the guide with a constant length of traverse, and a cam intermediate the reciprocating means and the thread-guide to impart an accelerated 90 rate of motion to the latter as it traverses in one direction and a decelerated rate as it traverses back in the opposite direction.

5. In a winding machine, the combination with a rotatable cop-holder, of traverse- 95 means for traversing the yarn on the holder, a traverse-lever for operating the traverse-means, means to reciprocate said traverse-lever bodily, and means to impart a continuous oscillating motion to the lever during 100 its reciprocation whereby to cause the traverse-means to be operated with a differential motion to lay the yarn in helices which are spaced closer together toward one end of the cop.

6. In a winding machine, the combination with a rotatable cop-holder, of traverse-means for traversing the yarn on the holder, a traverse-lever for operating the traverse-means, means to reciprocate said lever 110 bodily, and means to rock the lever in opposite directions during alternate strokes in its reciprocation, said rocking-means being operated continuously during the reciprocation of the lever.

7. In a winding machine, the combination with a rotatable cop-holder, of traverse-means for traversing the yarn on the holder, a traverse-lever for operating the traverse-means, means to bodily reciprocate said 120 traverse-lever, and means operated from the reciprocation of said lever to cause the latter to be continuously oscillated first in one direction and then in the other in accordance with its direction of movement during its 125 reciprocation.

8. In a winding machine, the combination with a rotatable cop-holder, of traverse-means for traversing the yarn on the holder, a reciprocable member, means to reciprocate 130

said member, a lever pivoted on said member and connected to operate the traverse-means, and means for continuously rocking the lever in opposite directions during alternate strokes in its reciprocation.

9. In a winding machine, the combination with a rotatable cop-holder, of traverse-means for traversing the yarn on the holder, a lever connected to operate the traverse-means, means to bodily reciprocate said traverse-lever, and a cam acting on said lever to continuously rock the latter to cause it to impart a differential rate of movement to the traverse-means.

10. In a winding machine, the combination with a rotatable cop-holder, of traverse-means for traversing the yarn on the holder, a lever for operating the traverse-means, means to bodily reciprocate said lever, and a fixed cam operating on said lever to rock the latter during its reciprocation to cause it to impart a differential rate of movement to the traverse-means.

11. In a winding machine, the combination with a rotatable cop-holder, of traverse-means for traversing the yarn on the holder, a lever for operating the traverse-means, a fixed cam, and means on the lever travelable on the cam to rock the lever during its reciprocation to cause it to impart a differential rate of movement to the traverse-means.

12. In a winding machine, the combination with a rotatable cop-holder, of traverse-means for traversing the yarn on the holder, a bell-crank lever connected to operate the traverse-means, means to bodily reciprocate said bell-crank lever, a fixed member having a curved cam-track, and means on the lever travelable on the cam-track to rock the lever during its reciprocation to cause it to impart a differential motion to the traverse-means.

13. In a winding machine, the combination with a traversing thread-guide, of a reciprocable slide, means to reciprocate the slide, a lever pivoted on the slide and connected to operate the guide, and a fixed cam engaging the lever to rock the latter during its reciprocation to cause it to impart a differential motion to the thread-guide.

14. In a winding machine, the combination with a traversing thread-guide, of a reciprocable slide, means to reciprocate the slide, a lever pivoted on the slide and connected to traverse the thread-guide, a fixed member having a curved guiding-track, and means on the lever travelable on the track to rock the lever to cause it to impart a differential motion to the thread-guide.

15. In a winding machine, the combination with a traversing thread-guide, of a lever for operating the guide, means to

bodily reciprocate the lever, and a fixed member having a curved cam-track operating on the lever to displace the latter during its reciprocation, said cam-track formed with a sharp bend at its end adapted to act on the lever to impart a rapid to-and-fro movement to the thread-guide at the end of its traverse to effect a quick reversal of movement of the guide.

16. In a winding machine, the combination with a rotatable cop-holder, of traverse-means for traversing the yarn on the holder, reciprocating-means for operating the traverse-means, means connecting the reciprocating-means with the traverse-means, and means for operating said connecting-means to displace the traverse-means relative to the reciprocating-means to effect a quick reversal of movement of the traverse-means.

17. In a winding machine, the combination with a rotatable cop-holder, of traverse-means for traversing the yarn to lay it in helical coils on the holder, means to reciprocate the traverse-means, and means intermediate the reciprocating-means and the traverse-means for causing an acceleration of movement of the traverse-means at the end of its traverse to effect a quick reversal of the coils of winding.

18. In a winding machine, the combination with a rotatable cop-holder, of traverse-means for traversing the yarn to lay it in helical coils on the holder, means to reciprocate the traverse-means, a lever connecting the reciprocating-means with the traverse-means, and means to rock said lever with a quick action to effect a sharp reversal in the movement of the traverse-means at the end of its traverse.

19. In a winding machine, the combination with a rotatable cop-holder, of a thread-guide for traversing the yarn on the holder, a reciprocable member, means to reciprocate said member, a lever pivoted on said member and connected to the thread-guide, and a cam acting on said lever to rock the latter to impart a quick reversal in the movement of the thread-guide at the end of its traverse.

20. In a winding machine, the combination with a rotatable cop-holder, of a thread-guide for traversing the yarn on the holder, a reciprocable slide, means to reciprocate the slide, a lever pivoted on the slide, a fixed cam-track formed with a sharp bend, and means on the lever engaging the cam to cause the latter to rock the lever to impart a quick reversal of movement of the thread-guide at the end of its traverse.

In testimony whereof I affix my signature.

GEORGE N. TAYLOR.
